VALVE TOOL

Application filed December 31, 1930. Serial No. 505,915.

The present invention relates to valve handling tools, and more particularly to an improved construction of tool adapted for application to the valves of internal combustion engines to facilitate the removal and replacing of the valves.

An object of the present invention is to provide a simply constructed and inexpensive tool which may be manipulated by hand to compress valve springs of the valves mounted in a valve in the head motor where in the head carries rocker arms for the compression of the valve springs, the tool being constructed with a pivotal or anchoring portion for co-operation with the posts upon which the rocker arms are mounted.

Another object of the present invention is to provide a valve tool in the form of a flat arm or lever which may be quickly and easily stamped or otherwise worked up from a metallic blank and which is provided with a hinged anchoring portion having an opening therethrough of a size adapted to bind upon the rocker arm post when the pivoted portion is canted incident to the swinging of the lever over the valve in the act of compressing the spring.

A further object of the present invention is to provide a hand operable valve spring compressing tool of a construction admitting of the quick and easy release of the locking ring, pin or other device carried upon the upper end of the valve stem by but a slight compression of the valve spring.

With the foregoing and other objects in view, the invention will be more fully described hereinafter, and will be more particularly pointed out in the claims appended hereto.

In the drawing, wherein like symbols refer to like or corresponding parts throughout the several views.

Figure 1 is a transverse section taken through the head of a cylinder of the overhead valve type and showing a valve tool

constructed according to the present invention applied thereto.

Figure 2 is a top plan view, partly broken away, of a valve tool constructed according to the present invention.

Figure 3 is an edge elevation of the same.

Figure 4 is a longitudinal central section taken through the tool, and

Figure 5 is a transverse section taken through the tool on the line 5—5 of Figure 2.

Referring now to the drawing, 10 designates a handle which is flat, of suitable length and at its outer end is shaped to the configuration of a hand grip 11 for facilitating the grasping of the outer end of the lever or arm 10 to manipulate the tool.

The inner end of the lever 10 is laterally enlarged to provide a head 12. The head 12 has an elongated substantially rectangular slot or opening 13 having opposed side walls 14 which are beveled or inclined outwardly and upwardly with respect to the upper face of the lever 10, as shown in Figures 2 and 5.

The outer end of the head 12 is recessed and provided with a pair of edgewise displaced lugs 15 which carry a cross pin or pivot 16 upon which is hinged an apertured anchoring lug 17.

The lug 17 is provided with a cylindrical aperture 18 of a size slightly greater than the diameter of the post 19, shown in Figure 1, which rises from the cylinder head 20 to support the usual rocker arms and the like from a part of an overhead valve motor.

The head 20 is provided with a post 19 adjacent each valve stem 21. Each valve stem 21 carries a valve head 22 upon its lower end which is seated in the usual manner in the block 20 and which is slideable through a bearing sleeve 23 fitted through the top of the head 20 and which serves as a guide for the valve stem 21.

The usual valve spring 24 is mounted about the sleeve 23 above the head 20 and lies beneath a cupped disc 25 which is held in engagement with the upper end of the spring 24.

by means of a split ring 26 or the like in the usual manner and which engages with the upper end of the valve stem 21.

5 A block 27 of wood or other suitable material is proportioned to fit in the cavity of the head 20 beneath the valve head 22 for holding the latter to its seat and with the upper end of the stem 21 above the bearing sleeve 23.

In operation or use of the valve tool, when 10 it is desired to remove a valve from the head 20, it is only necessary to slidably engage the pivoted lug 17 over the upper end of the post 19 of the head and slide the lug 17 downwardly over the post until the head 12 of the tool 15 comes into contact with the cupped disc 28 of the valve. The tool head 12 is so adjusted, by manipulation of the handle or lever 10, as to bring the upper end of the valve stem 21 into position through the elongated slot 13 of the head 12 and with the opposite sides of the 20 slot 13 in engagement with the upper face of the disc 25.

When the tool is in this position, and pressure is exerted upon the hand grip 11 to swing 25 the latter downward, the pivoted lug 17 will cant upon the post 19 and consequently will bind against the opposite sides of the post and grip the same to hold the lug 17 from vertical movement on the post. The cross pin or 30 pivot 16 admits of this automatic adjustment of the lug 17, and at the same time admits of the independent swinging of the lever or handle 10 when the latter is moved downward.

The downward movement of the lever 10 35 forces the head 12 thereof against the disc 25 and contracts the spring 24 so as to move the disc 25 and the head 12 of the tool downwardly away from the split ring 26, or other device which is seated on the valve stem.

40 Thus, as shown in Figure 1, when the tool is in releasing position, the ring or other device 26 may be easily removed from the valve stem, particularly since the side walls 14 of the slot in the head of the tool are beveled outwardly and upwardly so as to increase the width of the slot in the upper surface of the tool. Incident to this arrangement of the surface 14, it is apparent that the lever 10 45 does not have to be forced downwardly to as great an extent as would be the case were the opposite walls 14 disposed in parallel relation to each other.

To remove the tool, it is only necessary to relax upon the pressure on the handle or lever 55 10 and to slide the pivoted lug 17 upwardly on the post 19, preferably by direct application of the fingers to the lug. The lug 17 may be quickly and easily slid over the selected post 19 and may quickly withdrawn 60 therefrom so that the tool requires no setting of bolts, clamps or other devices which consume time in their application and adjustment and which necessarily provide a complicated structure. The valve springs 24 of the wall 65 series of valves of the head may be thus

quickly and easily removed, and as quickly and easily replaced by the use of the tool.

It is obvious that various changes and modifications may be made in the details of construction and design of the above specifically described embodiment of this invention without departing from the spirit thereof, such changes and modifications being restricted only by the scope of the following claims:

What is claimed is:—

1. A valve handling tool, comprising an elongated flat lever having a head at one end adapted to fit over a valve stem and having a slot through the head for the reception of the stem, a lug pivotally mounted on the outer end of the head and provided with an opening therethrough adapted to loosely engage over a rocker arm post and to bind thereon upon the swinging of the lever about the valve stem.

2. A valve removing tool, comprising an elongated flat lever having a hand grip on its outer end and provided with a laterally enlarged head on its inner end, said head having an elongated centrally disposed slot adapted to receive a valve stem upwardly therethrough and having upwardly and outwardly flaring side walls defining the sides of the slot, said head also having a pair of edgewise separated lugs at its outer end, a pivot pin carried across said lugs, an apertured lug mounted on said pivot pin and having an opening therethrough of greater diameter than that of the rocker arm post of an engine head for pivotally and loosely supporting the lug on the post, said lug adapted to cant on the post under pressure of said lever to bind the lug in adjusted position on the post and anchor the inner end of the lever adjacent the valve to be removed.

3. A valve removing tool for application to cylinder heads of overhead valve motors having rocker arm supporting posts and upwardly extending valve stems with their parts adjacent the posts, comprising an elongated flat lever having a head at one end with flat upper and lower sides and adapted to rest upon the cupped disc of the valve stem, said head having a longitudinal slot therein through which said stem is adapted to project, an apertured lug pivotally mounted on the outer end of the head and normally lying in the horizontal plane of the head and having an opening therethrough of greater diameter than that of the post for slidably engagement over the post and adapted to bind thereon when canted under pressure of the lever, said lever adapted to be disposed horizontally across the cupped disc and with the pivoted lug anchored on the adjacent post, whereby downward swinging of the outer end of the lever binds said lug on the post and forces said disc downwardly about the upper end of the valve stem.

4. A valve removing tool, comprising a relatively long flat lever having a handle on one end and a slotted head on the other end for receiving a valve stem therethrough, and an apertured lug hingedly mounted on the head of the lever and adapted for binding engagement over a rocker arm post adjacent the valve stem for anchoring the lever during operation.

10 In testimony whereof, we affix our signatures.
